CLAIM

I claim the ornamented design for a hat, as shown and described.

DESCRIPTION

FIG. 1 is a front elevation view of a hat showing my new design,

FIG. 2 is a rear elevation view thereof,

FIG. 3 is a side elevation view thereof,

FIG. 4 is a top plan thereof,

FIG. 5 is a three-quarter front perspective view thereof; and,

FIG. 6 is a three-quarter rear perspective view thereof.

The broken lines showing the crown are for illustrative purposes only, and form no part of the claimed design.

The broken lines on the brim of the hat represent stitching, forming part of the claimed design.
